Decatur, Ga. 30030

Primary Examiner—A. Hugo Word
Assistant Examiner—Monica A. Hannon
Attorney, Agent, or Firm—Jones & Askew

[73] Assignee: Timothy B. Toombs, Decatur, Ga.

[57] CLAIM

[] Term: 14 Years

The ornamental design for the decorative holder for a disposable lighter in the design of a torch, as shown and described.

[21] Appl. No.: 19,757

DESCRIPTION

[22] Filed: Mar. 10, 1994

FIG. 1 is a perspective view showing my new decorative holder for a disposable lighter in the design of a torch, wherein the disposable lighter and the flame indicated in broken lines are not part of the design;
FIG. 2 is a front view thereof;

[52] U.S. Cl. D27/148; D27/141

FIG. 3 is a right side view thereof, the left side view
being a mirror image;
